UNITED STATES PATENT OFFICE.

HORACE P. STEWART, OF GRAND RAPIDS, MICHIGAN.

MATCH-BOX.

1,047,718.

Specification of Letters Patent.

Patented Dec. 17, 1912.

Application filed June 4, 1912. Serial No. 701,600.

To all whom it may concern:

Be it known that I, HORACE P. STEWART, citizen of the United States, residing at Grand Rapids, in the county of Kent and State of Michigan, have invented certain new and useful Improvements in Match-Boxes, of which the following is a specification, reference being had therein to the accompanying drawing.

10 This invention relates to match boxes of the sliding feed type, and the principal object of the invention is to provide a box of this type in which the sliding feed will be so mounted that its movement will be regulated and, therefore, the slide be prevented from moving in a given direction beyond a desired point.

Another object of the invention is to so construct the plate directing the matches to the feed, that it will be readily removed when desired, and also to so construct the feeding plate that it may also be removed when it is desired to do so.

25 This invention is illustrated in the accompanying drawings, wherein:—

Figure 1 is a front elevation of the improved match box. Fig. 2 is a side elevation of the match box. Fig. 3 is a top plan view. Fig. 4 is a vertical sectional view through the box. Fig. 5 is a perspective view of the delivery plate which guides the matches to the forward end of the receptacle. Fig. 6 is a perspective view of the sliding delivery plate.

35 Referring to the accompanying drawings, it will be seen that this invention comprises the receptacle having the rear wall 10, the side walls 11, the front 12, a top 13, and a bottom 14. The top 13 terminates before reaching the rear wall 10, so that an opening 15 is formed in the upper portion of the receptacle through which matches may be placed into the receptacle. The front wall terminates short of the bottom 14, thus leaving an opening 16 in the lower forward portion of the receptacle through which the sliding delivery plate operates in order that matches may be drawn out through the forward lower corner of the receptacle. The bottom 14 extends beyond the front wall 12 and forms a support 17 upon which the sliding delivery plate travels. This support 17 is tapered as clearly shown in Fig. 3, and is provided at its forward end with an upward turning flange 18 which limits the outward movement of the delivery plate.

The sliding delivery plate shown in Fig. 6 is mounted in the lower portion of the receptacle as very clearly shown in Fig. 4, and comprises the inner portion 19 which is provided with the supporting flange 20 at its inner end to hold the inner portion of the sliding plate in spaced relation to the bottom 14. A transversely extending pocket 21 is formed at a point across the sliding delivery plate which will bring it just within the front wall 12 when the sliding plate is moved to an inward position as shown in Fig. 4, the plate at the outer edge of this pocket being crimped to form the rib 22 which comes in contact with the front wall 12, thus limiting the inward movement of the plate and preventing matches from flowing out when the delivery plate is in the position shown in Fig. 4. It is, of course, 75 obvious that if it were not for this rib 22 that when the plate was in the position shown in Fig. 4, the matches within the receptacle could readily flow out of the opening 16 across the outer portion 23 of the 80 delivery plate. This rib 22 also acts as an abutment against which to push when moving the delivery plate from the position shown in Fig. 2 to that shown in Fig. 4, the plate being drawn outwardly by means of 85 the flange 24.

A feeding and guiding plate is mounted in the rear portion of the receptacle so that the matches will be guided from the rear portion of the receptacle to the forward 90 portion, thus insuring the delivery of the matches into the pocket 21 when the box is in use. This feeding plate comprises the body portion 25 which has its upper portion bent to form the over-hanging flange 26 by 95 means of which it is supported by the upper edge of the rear wall 10 and has its lower portion bent to form the inclined section 27 which guides the matches toward the forward end of the receptacle.

When using this device, the receptacle is secured to a support by means of the screws 28 which pass through the set ears 29, and the device is then in position for use. The matches are placed in the receptacle through 105 the opening 15 and upon moving the sliding delivery plate to the position shown in Fig. 4, a match will drop into the pocket 21. The sliding delivery plate is then drawn outwardly as shown in Fig. 2 and the match 110 can then be removed from the pocket. When the delivery plate is in the outward position,

the inner portion of the plate is held at a sufficient distance above the bottom 14 to prevent matches from flowing out of the opening 16, and when in its inner position, 5 the rib prevents matches from flowing out. It will, therefore, be evident that as the slide is left in the position shown in Fig. 4, there is no danger of matches coming out of the receptacle and being wasted. If it is de- 10 sired to disassemble this box, the feeding plate can be very easily withdrawn through the opening 15 and the delivery plate can be drawn to its outer position and then by rais- 15 ing the forward end, can be drawn over the flange 18, thus permitting the entire delivery plate to be drawn out of the opening. It should be noted that under ordinary circum- 20 stances the flange 18 is sufficient to prevent the delivery plate from being drawn out be- yond a desired amount, thus preventing any danger of the delivery plate accidentally slipping out of the receptacle and becoming lost.

Having thus described my invention, what 25 I claim as new is:—

1. A match safe comprising a body portion having its bottom carried outwardly to form a support, the forward end of the support being bent to form an upwardly ex- 30 tending flange, said body portion being pro- vided with an inlet opening in its upper por- tion and with an outlet opening at the lower edge of the front wall, a feeding plate mounted in said body portion, a delivering 35 plate slidably mounted upon the bottom of said body portion and provided at its inner

and outer ends with oppositely disposed flanges and bent intermediate its length to form a receiving pocket and an abutment flange limiting the inward movement of said 40 delivering plate, the flange at the outer edge of the delivering plate contacting with the flange at the outer edge of said support to normally limit the outward movement of said delivering plate, said delivering plate 45 being formed of resilient material whereby it may be raised over the flange at the outer edge of said support to permit the removal of said delivering plate from said body portion. 50

2. A match safe comprising a receptacle having an inlet opening and having an outlet opening at the lower edge of its forward wall, a support extending from the bottom of said receptacle, a delivering plate slid- 55 ably mounted upon the bottom of said receptacle and upon said support, and having its inner end bent to form a depending flange and its outer end bent to form an upwardly extending flange, said plate being bent inter- 60 mediate its length to form a trough, and an upwardly extending flange in the outer edge of the trough forming a closure for the opening in the bottom of said receptacle when said plate is in the inner position, and a 65 feeding plate mounted in said receptacle.

In testimony whereof I hereunto affix my signature in presence of two witnesses.

HORACE P. STEWART.
